UNITED STATES PATENT OFFICE.

CHARLES OSBORNE FREER, OF NORTH WALTON, NEW YORK.

DEVICE FOR SUPPORTING AND PROTECTING SAP-PAILS.

SPECIFICATION forming part of Letters Patent No. 349,789, dated September 28, 1886.

Application filed July 15, 1886. Serial No. 208,123. (No model.)

To all whom it may concern:

Be it known that I, CHARLES OSBORNE FREER, a citizen of the United States, residing at North Walton, in the county of Delaware and State of New York, have invented new and useful Improvements in Devices for Supporting and Protecting Sap-Pails, of which the following is a specification.

My invention relates to improvements in devices for supporting and protecting sap-pails; and it consists of the peculiar construction and arrangement of parts, substantially as hereinafter fully described, and particularly pointed out in the claims.

15 In order that my invention may be fully understood, I will proceed to describe it with reference to the accompanying drawings, in which—

20 Figure 1 is a perspective view of my improved supporter in operative position upon a tree. Fig. 2 is a view of the parts of the supporter detached from each other.

25 In the said drawings, A designates a rectangular piece of metal, which is formed with a hole, a , through which the spile or sap-spout S is inserted, and said piece A is also formed below the hole a with a hook, a' , upon which the bail or body of a bucket or pail P is caught.

30 Each vertical side of the piece A is turned over, so as to form a loop, a^2 , and through these loops extend straight portions b of the sustaining-frame B. This frame B is made of a single piece of spring-wire, which continues 35 from the sections b in the straight sections b^7 to sections b' , the latter being so bent as to embrace the sides of the bucket, as shown. From the sections b the frame B continues upwardly in the straight sections b^8 , to form the loops b^2 , which add to the resilient action of the frame. From the loops b^2 the wire continues in the straight sections b^9 , which extend at right angles to sections b , and which terminate in loops b^4 , similar in form and purpose 40 to the loops b^2 . From the loops b^4 the wire continues in the sections b^5 , which converge toward toward each other and unite to form the twisted loop b^6 . The sections $b^5 b^6$ are turned back above and slightly oblique to the 45 sections b^3 . A cover, C, of metal or wood, is inserted between the sections $b^3 b^5$, and lies slantingly above the top of the bucket or pail.

By virtue of this construction no ice, snow, or other foreign substance can get into the sap in the pail, and the pail is held so securely 55 that the wind cannot blow it down. The usual spile or spout is used to alone support the device, so that all nails or other fastening devices can be dispensed with, and the device at the same time is securely supported. 60

Having thus described my invention, what I claim as new, and desire to secure by Letters Patent, is—

1. The combination of a carrying-plate having a transverse opening for the spout, the 55 upright arms fixed to the carrying-plate, the horizontal bars connected to the arms, the yielding arms b^5 , arranged alongside of the horizontal bar and connected thereto, and a cover interposed between the horizontal bars 70 and the yielding arms, substantially as described, for the purpose set forth.

2. The combination of a carrying-plate having a transverse opening for the spout, the supporting-frame B, connected to the plate 75 and comprising the horizontal bars b^3 , and the yielding clamping-bars b^5 , formed from a single piece of wire, and a removable cover, C, fitted between the horizontal and clamping bars and held in place thereby, substantially 80 as described, for the purpose set forth.

3. The combination of a carrying-plate, a supporting-frame, B, formed of a single piece of wire and comprising the upright arms connected to the plate, the horizontal yielding arms b^3 , arranged at right angles to the upright arms, and the clamping-arms b^5 , connected by the coils b^4 with the arms b^3 , and a cover, C, fitted between the arms $b^3 b^5$, substantially 85 as described, for the purpose set forth. 90

4. The combination, with the plate A, having hole a , hook a' , and bent sides a^2 , of the frame B, having straight sections $b b^3$, convergent sections b^5 , loops $b^2 b^4 b^6$, bent ends b' and the straight sections $b^7 b^8$, and the cover C, as 95 set forth.

In testimony that I claim the foregoing as my own I have hereto affixed my signature in presence of two witnesses.

CHARLES OSBORNE FREER.
